UNITED STATES PATENT OFFICE.

CHARLES SANDOZ MORITZ, OF TAVANNES, SWITZERLAND.

MEANS FOR ASSEMBLING LANTERN-WHEELS.

1,084,039.

Specification of Letters Patent.

Patented Jan. 13, 1914.

Application filed January 21, 1913. Serial No. 743,397.

To all whom it may concern:

Be it known that I, CHARLES SANDOZ MORITZ, a citizen of the Republic of Switzerland, and residing at Tavannes, Switzerland, have invented certain new and useful Improvements in Means for Assembling Lantern-Wheels, of which the following is a specification.

The present invention relates to improvements in the art of inserting the bars into the heads of lantern wheels, such as are used for instance in the manufacture of watches and clocks, and it relates more specifically to an improvement in means to be used in connection with suction machines, such as for instance described in my U. S. Patent 1,053,227, and the particular object of this present improvement is to facilitate the operation by so constructing the work-receiving perforate plate that the shafted heads of the lantern wheels can readily be inserted in the respective bores and are airtightly pressed against the perforate plate with the lower head, while the air is sucked through the system to draw the bars into the heads.

In order to make the invention more readily understood, I will now describe it with reference to the accompanying drawing, in which—

Figure 1 represents a vertical section through the work-receiving perforate plate with accessories, and two lantern wheels in elevation, the right hand one being only partly assembled. Fig. 2 shows a top view of the perforate plate with inserted lantern bodies. Fig. 3 shows a lantern body, with the bar receiving heads in section. Fig. 4 represents a sectional elevation through a suction apparatus, with the perforate plate in operative position.

The perforate plate *a* is provided with a plurality of axially extending bores *b*, which may be disposed in any desired manner, for instance, as shown, in a circle concentric to the central screw bolt *f*, which serves also as handle. The diameter of these bores, which extend clear through the plate, is larger than that of the upper head or plate *c* and smaller than that of the lower head *d* of the lantern pinions to be handled. It is obvious that for different sizes of lantern wheels plates showing bores of correspondingly different diameter must be supplied. In the lower face of the perforate plate is provided an air groove or channel *e*,

which in turn communicates with all of the bores *b*. Below the perforate plate is suspended by the screw bolt *f* the guard or support plate *g*. By turning the screw bolt, or by revolving the correspondingly threaded guard plate on the screw bolt, the support plate can be raised or lowered, according to the length of shaft of the lanterns under treatment.

The lantern wheel bodies comprise a shaft *i*, an upper head *c* with bores *c'* extending clear through the head, and a lower head *d* with bores *d'* extending only partway into the head, as shown in Fig. 3. These lantern bodies are now introduced by hand into the bores *b* of the plate *a*, and the lower heads *d*, which as above stated project circumferentially over the respective bore rim, are then pressed against the underface of the perforate plate by the support plate being raised to the requisite extent, as shown in Fig. 1. After all the bores *b* are provided with lantern bodies (Fig. 2) the plate *a* is airtightly fitted into the bowl or receiver A of the suction apparatus, shown in Fig. 4. A quantity of bars *h* is scattered over the plate *a*, and the aspirator B is started, when the bars will be sucked home into the small bores *c'* and *d'* respectively in the lantern heads, the air passing in the direction of the arrows.

As shown, the suction action may be aided by the shaking action of the eccentric drive C, which serves to keep the bars *h* on the plate *a* in constant agitation, so that they more readily drop into the bores in the pinion heads *c*. The air passes circumferentially by the heads *c* and through the still open bores *c'* into the bores *b*, and then into the annular channel *e*, and from there through the aspirator B, and the suction thus exerted forces the bars *h* into the seat-pairs *c', d'*.

What I claim is:—

1. In suction apparatus for assembling lantern wheels, a work-receiving plate, having a plurality of bores, an air channel open below and communicating in turn with all of said bores, and means for drawing air through said air channel and said bores.

2. In suction apparatus for assembling lantern wheels, a work-receiving plate having a plurality of axial bores, and an air groove communicating with said bores; means for assuring the operative position of the lantern bodies in said bores, and means

- for drawing air through said air channel and said bores.
3. In suction apparatus for assembling lantern wheels, a work receiving plate having a plurality of axial bores and an air groove communicating with said bores; adjustable means for keeping the lower heads of the lanterns airtightly pressed against said perforate plate, and means for drawing air through said air channel and said bores.
4. In suction apparatus for assembling lantern wheels, a work-receiving plate having a plurality of axial bores and an air groove communicating with said bores; a guard plate arranged below said perforate plate and adapted to support the shafts of the lantern bodies; means for adjusting the position of said guard plate relative to said
5. In suction apparatus for assembling lantern wheels, in combination, a work-receiving plate having a plurality of bores and an air groove connecting said bores; a guard plate underneath said perforate plate; a screw bolt adjustably securing said guard plate to said perforate plate, and means for drawing air through said air channel and said bores.

perforate plate, and means for drawing air through said air channel and said bores.

5. In suction apparatus for assembling lantern wheels, in combination, a work-receiving plate having a plurality of bores and an air groove connecting said bores; a guard plate underneath said perforate plate; a screw bolt adjustably securing said guard plate to said perforate plate, and means for drawing air through said air channel and said bores.

In testimony whereof I affix my signature in presence of two witnesses.

CHARLES SANDOZ MORITZ.
